(57) CLAIM

The ornamental design for a net light, as shown and described.

DESCRIPTION

FIG. 1 is a top, front and right side perspective of a net light showing my new design;

FIG. 2 is a top, rear and left side perspective view thereof;

FIG. 3 is a front elevational view thereof;

FIG. 4 is a rear elevational view thereof;

FIG. 5 is an enlarged view of portion 5 in FIG. 1;

FIG. 6 is an enlarged view of portion 6 in FIG. 1;

FIG. 7 is an enlarged view of portion 7 in FIG. 2; and,

FIG. 8 is an enlarged view of portion 8 in FIG. 2.

The broken lines surrounding the net light indicate that the claimed article has no specific length and width, the appearance of any portion of the article beyond the broken lines forms no part of the claimed design.

1 Claim, 8 Drawing Sheets
